UNITED STATES PATENT OFFICE.

PHILIP JOSEPH CLUNE, OF OTTAWA, ILLINOIS.

DESIGN FOR A BRICK.

Application filed November 25, 1927. Serial No. 24,269. Term of patent 3½ years.

To all whom it may concern:

Be it known that I, PHILIP J. CLUNE, a citizen of the United States, residing at Ottawa, in the county of La Salle and State of Illinois, have invented a new, original, and ornamental Design for a Brick, of which the following is a specification, reference being had to the accompanying drawing, forming a part hereof.

Figure 1 is a front elevation of a brick, showing my new design,

Figure 2 is a perspective view,

Figure 3 is a perspective view looking from the opposite end of Figure 2, and

Figure 4 is a transverse section.

What I claim is:

The ornamental design for a brick, as shown.

PHILIP JOSEPH CLUNE.
